WILLIAM M. WATTIE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

WEFT REPLENISHING MECHANISM FOR LOOMS

Application filed April 15, 1929. Serial No. 355,020.

This invention relates to improvements in weft replenishing looms, and it is the general object of the invention to provide a magazine frame reinforced below the transerrer arm 5 to increase the strength of the magazine and also assist in guiding a bobbin properly in transfer position.

The usual transerrer arm of a weft replenishing loom comprises a relatively large hub from which depend two substantially similar legs which support the lay engaging latch. Extending substantially horizontally from the hub is an L-shaped arm which extends rearwardly and then turns to extend 15 substantially parallel to and above the lay. It has been found in practice that breakage of the transerrer arms is more likely to occur in the horizontal portion thereof and it is an important object of my present invention to provide the transerrer arm of a built-up unit one portion of which is provided for the latch and the other portion 20 of which is the bobbin engaging part of the transerrer, the latter part being replaceable 25 without requiring renewal of the part which supports the latch.

It is a further object of my present invention to provide the two parts of the transerrer arm with spaced separate bearings 30 through which extend preferably a common supporting stud, the spaced bearings tending to prevent uncertainty of motion of the transerrer arm and thereby insuring more perfect transfers of bobbins into the active 35 shuttle.

As customarily made the transerrer arm and latch are connected by a simple pivot and any movement of the latch out of the path of the bunter on the lay is effected by 40 gravity. When a shuttle is misplaced on a transferring beat of the loom and revocation of the magazine is required, the support for the latch is ordinarily lowered and if the latch should be slow in its descent it will be 45 engaged by the lay and an improper transfer will result. I have found with looms running at a high rate of speed that the time interval for the latch to clear the bunter on revoking picks is very small and as a result improper 50 transfers occur. It is a further object of my

present invention to provide means which will assist gravity in lowering the transerrer latch, said means preferably though not necessarily comprising a resilient interconnection between the latch and the transerrer arm effective to insure immediate and rapid descent of the latch when the shuttle is not properly placed. 55

It is a still further object of my invention to provide a composite transerrer arm having two independent parts each of which is removable from the loom without disturbing the other part. This result is attained as shown herein by pivoting the transerrer arm members or parts to a stud on opposite sides of the supporting structure for the stud. 60

Multicolor weft replenishing magazines customarily employ two substantially parallel spaced plates between which the bobbins lie. The inner plate near the selvage of the cloth has mounted thereon supports for the butt of the bobbin and also operating slides which effect release of the bobbins from the stacks. The previously mentioned portion of the transerrer arm which is parallel to the lay extends through and moves in an arcuate slot formed in the inner plate. Heretofore this slot has been open at the bottom, thus weakening the lower portion of the inner magazine plate. It is an important object of my present invention to link the front and back lower portions of the inner plate below the slot so that the plate will be stronger than previously. When such a change is made it is necessary to provide clearance on 70

the transerrer arm and this I accomplish by making a recess in that part of the transerrer arm which extends parallel to the lay, said recess, when the transerrer arm is in its lowest position, receiving the link which defines the bottom of the slot. That side of the link next the reserve bobbins is continuous with the adjoining side or surface of the magazine plate, and for this reason guides the bobbin moving toward transfer position. 75

With these and other objects in view which will appear as the description proceeds, my invention resides in the combination and arrangement of parts hereinafter described and set forth in the claims. 80

In the accompanying drawings wherein a convenient embodiment of my invention is set forth,

Fig. 1 is a side elevation of my invention applied to a magazine as viewed from the center of the loom,

Fig. 2 is a horizontal section on line 2—2 of Fig. 1,

Fig. 3 is a detailed substantial vertical section on line 3—3 of Fig. 2, with some of the parts broken away for the sake of clearness, and

Fig. 4 is a vertical section on line 4—4 of Fig. 1 showing the transerrer arm in lowered position from that which it occupies in Fig. 1, and showing the relation it sustains to the link.

Referring to the drawings I have shown a magazine M having a foot 10 which is supported by a loom frame 11. The magazine has a stand 12 provided with a hub 13 through which extends a relatively large stud 14. An inside plate 15 cast integral with the stand has slidably mounted thereon a plurality of vertical bobbin controlling members 16. The forward lower portion of the plate 15 has pivoted thereto as at 17 a front yieldable bobbin support 18 for the butts of the bobbins B. The rear butt support 19 is indicated in dotted lines in Fig. 1.

At the time of transfer one or another of the members 16 will have a vertical reciprocating movement to rock the corresponding cradle 20 and effect discharge of a bobbin from the associated stack. A released bobbin will move downwardly and be held in transfer position by the supports. During the forward beat of the lay L the bobbin on the supports is transferred into the shuttle S by mechanism to be described. The magazine is of the multicolor type and may be of the usual construction, the forward butt giveaway 18 being substantially the same as that shown in Hume & King No. 1,703,935 and the rear support being substantially the same as that shown in patent to Ryon No. 1,366,950.

In carrying my invention into effect I provide a latch supporting element 30 having a hub 31 pivoted on stud 14 and held against longitudinal movement on said stud by the hub 13 and a pin 32 extending through one end of the stud. The latch member 30 is provided with a pair of depending legs 33 which have pivoted thereto a latch holder 34. The lay engaging latch 35 is held in a slot 36 in the holder by means of bolt 37 and said latch is adjusted longitudinally with respect to the holder by means of screw 38.

A leaf spring 39 shown more particularly in Fig. 1 has a lower portion thereof 40 secured by screws 41 to the upper portion of the latch 35. The upper end of said spring is bent slightly as at 42 and has sliding engagement with the rear face 43 on one of the

legs 33. A rod 44 which is part of the ordinary multicolor magazine extends downwardly from the upper portion of the magazine and extends under the latch, said rod moving upwardly preparatory to transfer to raise the latch 35 into the path of the bunter 45 on the lay. The spring 39 acts normally to hold the latch 35 depressed and upward movement of the latch by means of the rod 44 places the spring 39 under additional stress.

The transerrer mechanism consists of a second member 46 having a hub 47 pivoted on stud 14 between a shoulder on the stud 14 and the hub 13. Extending rearwardly from the hub 46 is an arm 48 which is bent at right angles and projected over and substantially parallel to the lay and having a bobbin engaging foot 49. The foot 49 extends through a slot 50 formed in the plate 15 of the magazine frame. The rearwardly extending arm 48 has cast integrally therewith a lug 51 which projects into a forked arm 52 having a pair of elements shown in dotted lines in Fig. 1, and extending rearwardly from and rigid with the first named transerrer mechanism member 30. A bolt 53 extends through the elements of the arm 52 and lug 51 to prevent relative angular movement between the members 30 and 46 of the transerrer mechanism, and the bolt is held against longitudinal movement by nut 57.

The foot 49 extending through the slot 50 is provided on the under side thereof with an upwardly extending recess 54 which receives a link 55 cast integrally with the plate 15 and extending across the bottom of the slot 50. This link connects and strengthens the lower parts of the plate 15 lying in front of and behind the slot 50. In order that the transerrer arm may normally be held in raised position I provide a tension spring 60 the upper end of which may be fixed to any approved part of the magazine frame not shown and the lower portion of which is operatively related to a stud 61 projecting from the transfer member 30. In order to limit downward motion of the transerrer arm should spring 60 break, I form on the member 30 a lug 70 through which is threaded a screw 71 the head of which is placed to engage a boss 72 on the stand 12.

Under normal conditions the parts will be in the position shown in Fig. 1, the latch 35 being held beneath the bunter 45 when the latter is in its extreme forward position, partly by gravity and partly by the resilience of spring 39. When a transfer is about to take place the rod 44 is raised, thereby elevating the latch 35 into the path of the bunter 45 and at the same time placing the spring 39 under additional stress. If the shuttle be properly placed the bunter will engage the latch as the lay advances and the transerrer arm member 30 will be given a counter-clock-

wise movement around stud 14 as viewed in Fig. 1. By reason of the connection between the members 30 and 46, that is, the arm 52 and lug 51, the bobbin engaging member 49 will be depressed to move the bobbin which is resting on the supports into the shuttle. When the transerrer arm is in its lowest position it will be in the position shown in Fig. 4 with respect to the plate 15.

10 Should it be necessary to revoke the indication of the magazine after the latch has been raised mechanism not shown but well understood and described in Patent No. 1,030,748 will operate to depress the rod 44. 15 Downward movement of the latch under influence of gravity will be facilitated by the spring 39, which under these conditions will move the latch down with a quicker motion than has been possible heretofore when gravity alone was relied upon to move the latch out of the path of the bunter. During transfer the spring 60 is elongated, but after transfer is completed the spring 60 will contract to raise the transerrer arm to the normal 20 position shown in Fig. 1.

Should the bobbin engaging member 49 become broken or so badly damaged as to be unfit for further use it is necessary merely to remove the bolt 53 by loosening the nut 57, 30 thereby disconnecting the member 46 from the member 30. The new member 46 can then be placed on the stud 14 and the bolt 53 returned to its normal position. In this way the expense of supplying a complete transerrer arm is avoided, inasmuch as the member 30 and all the parts associated therewith may be saved.

From the foregoing it will be seen that the magazine frame through which the transerrer arm extends is strengthened by the link 55 and is therefore stronger than the plates which have heretofore been in use. It will further be noted that the transerrer arm is so formed as to be able to move to its lowest position without interference with the link 55. Also, the link acts as a guide to direct a bobbin moving toward transfer position so that it will come to rest correctly on the bobbin butt supports 18 and 19 without 45 engaging the sides of the slot 50.

Having thus described my invention it will be seen that changes and modifications may be made therein by those skilled in the art without departing from the spirit and scope 55 of the invention and I do not wish to be limited to the details herein disclosed, but what I claim is:

1. In a weft replenishing mechanism for a loom operating with reserve bobbins adapted to move to common transfer position, a stationary plate forming part of the magazine and holding the reserve bobbins preparatory to transfer, a transerrer arm extending through the plate and having a portion to 60 engage a bobbin in transfer position, said

plate having an opening therethrough having a continuous outline and through which the transerrer arm extends, the part of the plate lying below the opening for the transerrer arm acting as a guide to direct a bobbin toward transfer position. 70

2. In a weft replenishing mechanism for a loom having a lay and operating with reserve bobbins adapted to move to a common transfer position, a stationary plate forming part of the mechanism arranged above and extending transversely of the lay, there being a substantially vertical slot in the lower part of the plate to divide the latter into two parts, a transerrer arm to extend through the slot 75 and cooperate with a bobbin in transfer position, and a link rigid with the two parts of the magazine to stiffen said parts, said link extending across the bottom of the slot, and acting as a guide to direct a bobbin toward 80 transfer position. 85

3. In a weft replenishing mechanism for a loom having a lay and operating with reserve bobbins adapted to move to a common transfer position, a vertically disposed plate forming part of the magazine, the bobbin to be transferred being disposed on one side of the plate, an opening extending from one side to the other side thereof through the plate, the plate being continuous along the lower edge thereof and extending under the bottom of the opening and a transerrer arm lying partly on the side of the plate opposite the bobbins and extending through the opening and lying partly on the side of the plate 90 on which the bobbins are located, the lower part of the plate under the opening acting as a guide to direct a bobbin toward transfer position. 95

4. In a weft replenishing magazine, a plate 100 on one side of which reserve bobbins are stored to move to transfer position, a transverse opening extending through the plate, said opening having a closed periphery which is located within the outline of the plate, and a transerrer arm extending through the opening from one side of the plate to the other, the arm receiving power on one side of the plate and having a bobbin engaging portion on the other side of the plate, 105 that part of the plate lying below the opening having a surface continuous with the said side of the plate and acting to guide a bobbin moving toward transfer position. 110

5. A weft replenishing loom operating 120 with a plurality of reserve bobbins any one of which may move to transfer position, a pair of spaced supports for the butt of a bobbin in transfer position, a plate adjacent said supports to engage and prevent endwise 125 movement of the bobbins, a transerrer member extending through the plate to force a bobbin between the supports at the time of transfer, said plate having a portion thereof lying under the transerrer arm and extend- 130

ing between the supports to define the guide which is substantially continuous with that part of the plate which prevents endwise movement of the bobbins.

5 In testimony whereof I have hereunto affixed by signature.

WILLIAM M. WATTIE.
